CLAIM

The ornamental design for a remote control, as shown and described.

DESCRIPTION

FIG. 1 is a front perspective view of a remote control showing our design;

FIG. 2 is a front view thereof;

FIG. 3 is a rear view thereof;

FIG. 4 is a side view thereof,

FIG. 5 is a side view thereof, opposite that shown in FIG. 4;

FIG. 6 is a top view of the remote control;

FIG. 7 is a bottom view thereof;

FIG. 8 is a front perspective view of the remote control positioned in an uninterruptible power system;

FIG. 9 is a front perspective view of the remote control in an environmental use condition; and,

FIG. 10 is a front perspective view of the remote control in an environmental use condition.

The broken lines in the drawings illustrate portions of the remote control that form no part of the claimed design.
